BUNK STAKE EQUIPMENT

Harold A. Puxon, Vancouver, British Columbia,
Canada

Application October 13, 1947, Serial No. 779,431

4 Claims. (Cl. 280—147)

1

This invention relates to improvements in bunk equipment, particularly for logging trucks and trailers, although it may be used on other types of vehicles, such as railway cars.

An object of the present invention is the provision of bunk equipment in which the stake is releasable and falls completely away from the bunk.

Another object is the provision of bunk equipment in which the stakes are interchangeable, and different sizes may be used for different jobs.

A further object is the provision of apparatus of the nature described including few moving parts.

A still further object is the provision of collapsible bunk equipment in which the control lever is not under tension or compression when the bunk is loaded.

Yet another object is the provision of bunk equipment of such a design that it may be very strongly constructed for heavy duty purposes.

Still another object is the provision of bunk equipment in which the stake can be put in place while the mechanism is in its locking position.

With the above and other objects in view, the present invention consists essentially of bunk equipment comprising a logging bunk, a support at one end of the bunk, a stake adapted to rest on the support, a tongue projecting inwardly from the stake above the bottom thereof, means on the bunk for removably gripping the tongue, and locking means for retaining the gripping means in the gripping position, said locking means being operable to release the gripping means to allow the stake to fall away from the bunk as more fully described in the following specification and illustrated in the accompanying drawings, in which

Figure 1 is a plan view, partly broken away, with the stake removed.

Figure 2 is a longitudinal section through the bunk.

Figure 3 is an end elevation of the apparatus, and

Figure 4 is a perspective view of the bunk stake.

Referring more particularly to the drawings, 10 is a bunk which is constructed in any suitable manner. For heavy duty work, the bunk may be formed of side beams 11 joined together at their upper edges by a supporting member 12, the latter being formed with a slot 13 therein at the end of which a removable stake is to be carried. A support 16 is mounted below and carried by this end of the bunk. This support consists of a socket arrangement adapted to receive the lower end of a stake 19. When the stake is carried by the

2

support, it extends upwardly through the slot 13 in the top of the bunk.

The stake 19 has a tongue 20 projecting inwardly therefrom above the bottom thereof. This tongue is positioned below the top of the bunk and it is preferably formed with a head 21 at its outer end.

Suitable means is provided on the bunk for removably gripping the tongue 20 to lock the stake 10 in its vertical position when resting on the support 16. For this purpose, a pair of opposing and co-operating locking arms 24 and 25 are pivotally mounted at 26 and 27, respectively, side by side on the bunk. A plate 28 may extend

15 between the side beams 11 spaced below the top of the bunk to carry said locking arms. The locking arms are formed with corresponding recesses 30 and 31 in their inner surfaces adjacent the outer ends thereof for receiving the head 21

20 of the tongue 20 when the stake is in its operative position. The arms 24 and 25 may be locked in position while gripping the tongue head so that the stake is firmly held in position.

Means is provided for pivoting the arms into 25 their locking positions, locking them in this position, and releasing said arms to permit the stake to fall away from the support 16 and the end of the bunk.

The inner surfaces of the locking arms diverge 30 inside the pivots 26 and 27, as at 34 and 35. A locking wedge 36 is movably mounted between the diverging surfaces 34 and 35. When the wedge is moved outwardly in relation to the bunk, the outer ends of the locking arms are pivoted 35 towards each other to grip the tongue of the stake. When said wedge is moved in the opposite direction, the outer ends of the locking arms pivot away from each other to release the tongue.

As the load on the bunk will roll off when the 40 stake is removed, it is desirable that the person releasing the stake is near the opposite end of the bunk. For this reason, a control lever or arm 39 is provided which is connected to the locking wedge 36 at one end and extends along the bunk 45 to a point adjacent its opposite end. The control lever or arm 39 has an elongated slot 40 in one end, through which a pin 41 extends, said pin connecting the arm to the locking wedge. One or more brackets 42 may be provided through 50 which the control lever or arm 39 extends. The arm is provided adjacent its opposite end with a tongue 43. A control slot is provided in the side of the bunk, said slot actually consisting of a horizontal slot 44 and a vertical slot 45 extending downwardly therefrom. When the tongue 43

rests in the vertical slot, the pin 41 rests in the inner end of the slot 40 at the opposite end of the arm and the locking wedge 36 is held between the diverging ends of the locking arms 24 and 25.

In order to release the stake, the tongue 43 of the control lever or arm 39, which projects through the side of the bunk, is driven upwardly and then horizontally into the slot 44. The elongated slot permits this movement without moving the locking wedge. Then the tongue 43 may be driven along the slot 44 to withdraw the locking wedge and permit the locking arms to release the stake. The pressure of the load on the stake forces the latter away from the locking arms so that it drops clear of the bunk.

After having released the stake, the operator may then move the control arm to return the locking arms to their locking position. After the load has been removed from the vehicle, it is only necessary to replace the stake in the support 16. As the stake is dropped into the support, the head 21 of the tongue drops into the recesses 30 and 31 of the locking arms. With this arrangement, one man can release the load and then replace the stake.

What I claim as my invention is:

1. Bunk stake equipment comprising a logging bunk, a support at one end of the bunk, a stake adapted to rest on the support, a tongue projecting inwardly from the stake above the bottom thereof, locking arms pivotally mounted on the bunk for removably gripping the tongue, and a locking wedge for wedging the arms into and retaining them in the gripping position, said wedge being adapted to be withdrawn to release the locking arms to allow the stake to fall away from the bunk.

2. Bunk stake equipment comprising a logging bunk, a support at one end of the bunk, a stake adapted to rest on the support, a tongue projecting inwardly from the stake above the bottom thereof, locking arms pivotally mounted on the bunk for removably gripping the tongue, a locking wedge for wedging the arms into and retaining them in the gripping position, a bar extending inwardly from the locking wedge along the side of the bunk, a slot formed in the bunk at the inner end of the bar, said slot having vertical and horizontal sections, and a stop on the bar riding in the slot, said stop resting in the vertical section to lock the wedge in the retaining position

and being movable into and along the horizontal section to release said wedge.

3. Bunk stake equipment comprising a logging bunk, a support at one end of the bunk, a stake adapted to rest on the support, a tongue projecting inwardly from the stake above the bottom thereof, a head formed on the outer end of the tongue, a pair of co-operating locking arms pivotally mounted side by side substantially midway between their ends on the bunk adjacent the support, said arms having corresponding recesses in their inner surfaces outside the pivots for receiving the head of a tongue, said inner surfaces diverging from each other on the inside of the pivots, and a locking wedge movable between the diverging surfaces of the arms to cause the latter to grip a head in the recesses thereof, said wedge being adapted to be withdrawn to release the locking arms to allow the stake to fall away from the bunk.

4. Bunk stake equipment comprising a logging bunk, a support at one end of the bunk, a stake adapted to rest on the support, a tongue projecting inwardly from the stake above the bottom thereof, a head formed on the outer end of the tongue, a pair of co-operating locking arms pivotally mounted side by side substantially midway between their ends on the bunk adjacent the support, said arms having corresponding recesses in their inner surfaces outside the pivots for receiving the head of a tongue, said inner surfaces diverging from each other on the inside of the pivots, a locking wedge movable between the diverging surfaces of the arms to cause the latter to grip a head in the recesses thereof, a bar extending inwardly from the locking wedge along the side of the bunk, and means at the inner end of the bar for locking the bar to hold the wedge in the retaining position.
